UNITED STATES PATENT OFFICE.

ERCOLE CAVICCHI, OF QUINCY, MASSACHUSETTS.

POLISHING-MACHINE FOR FLOORS.

1,294,398.

Specification of Letters Patent. Patented Feb. 18, 1919.

Application filed November 22, 1915. Serial No. 62,755.

To all whom it may concern:

Be it known that I, ERCOLE CAVICCHI, a citizen of the United States, and resident of Quincy, county of Norfolk, State of Massachusetts, have invented an Improvement in Polishing-Machines for Floors, of which the following description, in connection with the accompanying drawing, is a specification, like characters on the drawing representing like parts.

This invention relates to improvements in grinding or polishing machines of the type in which a rotary grinding or polishing member is pushed backward and forward over the surface to be polished, such as marble, mosaic, terrazzo or other composition flooring and comprises certain improvements upon the machine disclosed in my prior Patent No. 1,126,615 which was granted Oct. 26, 1916.

In the use of machines of this character a considerable amount of water is supplied to increase the rapidity of abrasion and considerable difficulty has been experienced in machines of this type by reason of the centrifugal action of the grinding members forcing the water and mud away from the center of the machine so that a portion of the grinding surface would run dry.

One of the objects of the present invention is to provide a grinding tool having abrasive members so disposed that each of the abrasive members will remain continuously in contact with the surface being polished; the disposition of the members being also such as to provide for the free circulation of water or mud between said members so that each member will always be provided with a sufficient amount of water to enable it to act efficiently.

Another feature of the invention consists in so supporting the abrasive members that they may be readily removed for the purpose of repair or replacement.

Another object of the invention is to provide a means whereby the entire series of rotary grinding members together with the driving head therefor may be readily removed from the driving mechanism to facilitate transportation of the machine and also to permit easy repairing of the parts.

In machines of this character with which I have been familiar the motor for actuating the driving mechanism is supported upon a truck, the polishing mechanism being car-

ried by the truck at a considerable distance beyond the end of the motor so that in use it has been necessary to place heavy weights above the grinding mechanism in order to obtain the desired efficiency of operation.

Another improved feature of the present invention consists in placing the axis of the polishing mechanism directly beneath the motor so that the greater portion of the weight of the motor will be carried directly by the polishing mechanism thereby greatly increasing the normal pressure between the polishing tools and the surface being treated.

Other features of the invention will more fully appear from the following description, the accompanying drawings, and will be pointed out in the annexed claims.

In the drawings:

Figure 1 is a vertical longitudinal sectional view of a polishing machine embodying the preferred form of my invention, the motor being shown in elevation,

Fig. 2 is a plan view of the machine the motor having been removed,

Fig. 3 is a plan view of the rotary driving head for the polishing tools illustrating the manner in which the tools are connected to said guiding member.

Fig. 4 is a bottom plan view of the rotary driving member and polishing tools illustrating one of the preferred forms of tools,

Fig. 5 is a side elevation of the mechanisms shown in Figs. 3 and 4,

Fig. 6 is a detail longitudinal sectional view of one of the polishing tools showing the universal connection between it and the rotary driving head,

Fig. 7 is a bottom plan view of a series of polishing tools in which the abrasive surfaces are of cylindrical form having tapered ends removably seated in corresponding sockets, and,

Fig. 8 is a detail vertical sectional view on lines 8-8, Fig. 7.

The polishing machine illustrated herein comprises a base or platform 1, preferably supported at one end upon a truck and at the opposite end provided with a downwardly offset portion 2 having a boss 3 providing a journal for a driving shaft 4 adapted to actuate a rotary driving head which will hereinafter be described. The offset portion 2 may conveniently be made in the form of a gear casing the outer end providing a journal 5 for a countershaft 110

adapted to support suitable gears for transmitting power from the motor to the driving shaft 4. A suitable motor, such as an electric motor 6 is rigidly secured to the base of the platform 1 and its shaft is provided with a gear 7 which meshes with a gear 8 rigidly mounted upon a stud shaft 9 which is mounted in the bearing 5 in said platform extension, the opposite end of the stud shaft 9 being mounted in a socket 10 in a plate 11 which is secured to the platform by bolts 12. The plate 11 is also provided with a downwardly extending boss 13 in which is formed a thrust bearing 14 for the upper end of the shaft 4. The thrust bearing may be provided with antifriction members of any usual type such as plates, disks or balls. The shaft 9 desirably may be provided with an axial duct 15 provided with radial apertures extending to the surface of the shaft and connecting with a duct 16 leading to said thrust bearing. The stud shaft 9 preferably is rigidly secured in the socket 10 by a set screw 17 and is preferably made of a sufficient length to extend beyond the end of the gear casing and apertured to receive a pin 18 by which the shaft may be readily withdrawn if it is desired to dismantle the gearing.

30 A gear 19, having an extended hub 20 is preferably rotatably mounted upon the stud shaft 9 and the hub of the gear 8 is rigidly secured to the hub of the gear 19 by a key so that the gears 8 and 19 will rotate together upon the shaft 9. The gear 19 engages a beveled gear 21 which is rigidly secured upon the driving shaft 4. It will therefore be obvious that the rotation of the shaft of the motor will transmit power through the gears 7, 8, 19 and 21 to the shaft 4 which serves to drive or actuate the rotary driving head for the polishing tools. Heretofore the gearing connecting the motor with the grinding or polishing mechanism has been so disposed that a relatively small portion of the weight of the motor has been carried by the polishing mechanism thereby rendering it necessary to place a heavy weight above the polishing mechanism. By reason of the novel construction above described the shaft 4 is placed directly beneath the motor so that a considerable portion of the weight of the motor is carried directly by the polishing mechanism through the shaft 4. The opposite end of the platform 1 may be supported in any convenient manner as by means of a truck having a single or preferably a plurality of wheels.

60 As illustrated herein the wheels 22, are rotatably mounted upon an axle 23 which is carried by a frame comprising arms 24, 25 pivotally secured to a shaft 26 mounted in the offset portion 2 of the platform, said arms 24, 25 being connected by a cross piece

26* to maintain the same in parallelism and to provide a rigid frame therefor.

The axle 23 of the wheels is adjustably secured to the platform by means of a locking rack 27, 27' having a recess 28 adapted to engage the axle 23, said racks being connected to a shaft 29 carried by brackets 30 secured to the lower face of the platform 1. The rack 27 desirably is provided with an integral offset lever 31 adapted to be depressed by the foot of the operator to disengage the rack 27 from the axle 23. The rack 27 is, however, normally maintained in engagement with the axle by a helical spring 32 surrounding the shaft 29 and secured at one end to the rack 27 and its opposite end engaging the under face of the platform.

In order to prevent the complete disengagement of the rack 27 from the axle 23 and consequently the dropping of the platform I have found it convenient to provide the rack with a preferably integral keeper 33 which will permit the rack to be shifted so that any of the recesses thereof may be engaged with the axle but which will prevent the entire disengagement of the rack.

A suitable handle 34 may be connected to the platform by brackets 35, 36 which may be secured together and to the handle by bolts 37. A switch 38 located upon the handle within reach of the operator may conveniently be provided for the purpose of controlling the motor.

While the mechanism above described provides a means for locating the axis of the driving head for the abrasive members beneath the motor with means for maintaining the platform level notwithstanding the wearing away of the abrasive members it will be obvious that other mechanisms of equivalent function may be provided, the principal feature of the mechanism thus described residing in the placing of the axis of the driving head beneath the motor so that the weight of the latter will bear directly upon it, and providing suitable means for adjusting the height of the platform to compensate for the wearing of the abrasive members.

The driving mechanism is preferably detachably connected with the driving head in order that the latter may be readily removed for repair and other purposes.

This is accomplished in the preferred form of the invention illustrated herein by providing the shaft 4 with an enlarged end 40 of angular, preferably rectangular cross section, said end being adapted to fit in a corresponding socket 41 in a hub 42 extending downwardly from the center of the driving head 43. The driving head 43 is preferably in the form of a spider having three arms 44, 45, and 46 extending radially from the head of a preferably integral circum-

ferential ring 47. Each of the arms 44, 45, and 46 is preferably provided with a tapering aperture 48 adapted to receive a stud 49 tapered to fit said aperture and adapted to be retained therein by a cotter pin. The lower end of each stud is enlarged to provide a spherical head 50 adapted to be seated in a corresponding recess 51 in the plate 52 which carries the abrasive members.

10 The spherical head 50 may conveniently be retained in its socket 51 by a cap plate 53 centrally apertured to fit the outer portion of the head 50 and provided with slots to receive lugs 54 extending upwardly from the plate 52, the cap 53 being retained in place by cotter pins 55 passing through apertures in said lugs.

Other forms of universal coupling may of course be utilized to connect the driving head with the polishing tools. It is however desirable that such connections be utilized as will permit the easy removal of the polishing tool from the driving head.

In the present case as in the machine disclosed in my prior patent the driving head is provided with not more than three polishing tools which are connected to the driving head by means of universal joints, consequently the tools are maintained in contact

30 with the surface being polished at all times.

In my former patent the preferred form of polishing tool described and claimed therein was in the form of a hollow elliptical abrasive member adapted to be reversed so that the sides might be caused to wear uniformly. In the present embodiment of my invention each of the polishing tools is provided with three abrading blocks triangularly disposed. By this arrangement not only is each tool caused to engage continuously the surface being polished but each abrading block of each tool is likewise maintained in engagement with the surface being treated; furthermore these abrading blocks are so located as to cause the circulation of water from one to another.

In Figs. 3 and 4 I have illustrated a driving head as provided with three polishing tools 56, 57, 58. These tools are preferably 50 of the same form, each comprising a substantially triangular plate 52 having recesses 60, 61 and 62 disposed in triangular arrangement in which are seated respectively abrading blocks 63, 64 and 65.

55 These abrading blocks are spaced at different radial distances from the axis of rotation of the driving member and are so disposed that water or mud encountered by the abrading block 64 will be partly thrust inward until it is engaged by the abrading block 63 and by the latter still farther inwardly until it engages the abrading block 65.

Each of the polishing tools 56, 57, and 58 65 is pivotally secured within the area of the

triangle formed by lines joining the abrading block by a universal joint connection such as is illustrated in Fig. 6, and above described, so that each block is free to tilt in any direction.

70

In order however to prevent an undesirable amount of tilting when an unusual obstruction is encountered the under face of the driving head 43 is provided with downwardly extending lugs 66 located above and substantially adjacent the corners of the plate 52. In order to prevent relative rotation between the polishing tools and the rotary driving head it is provided with downwardly extending lugs 67 which engage recesses 68 and 69 in the adjacent ends of the polishing tools. The recesses 68 and 69 are of a sufficient size to permit the polishing tools to tilt freely in the manner aforesaid.

85

It will be obvious that other forms of polishing tools may be utilized within the spirit of my invention and the scope of the following claims, the principal feature of the invention residing in the fact that each polishing tool is provided with members disposed in triangular relation so that all of the tools may be caused to engage the surface being treated at all times.

90

It may be noted in this connection that one or two abrading tools might be utilized with the same general function and without the susceptibility of abrading either as would be the case if more than three tools were used. In my prior application the claims cover a construction in which three polishing tools are provided upon a rotary head each of said polishing tools having a single abrading surface. The present invention and the claims herein are intended to cover the rotary polishing machine having either one, two or three polishing tools and each tool provided with two or three abrading members.

100

In Figs. 7 and 8 a different form of abrading tool is illustrated in which the abrading blocks are cylindrical in form and are seated in tapered apertures in the plate 52. As illustrated in Fig. 7 the abrading blocks are used, a single block 70 being placed at the apex of the triangle, another cylindrical block 71 being disposed more nearly the center of rotation and a pair of cylindrical blocks 72 located at a greater distance from the center of rotation than either of the blocks 71. In this construction the blocks 72 are in effect a single grinding member constituting one of the triangularly disposed series.

115

These abrading blocks are preferably of corundum and are provided with beveled upper ends 73 which are seated in similarly beveled or conical apertures 74 which preferably extend through the plate 52 as illustrated in Fig. 8. This forms a convenient 120 125 130

- construction for assembling and replacing the grinding members. Heretofore the abrading blocks have been secured in place in the polishing tool by adhesive mediums such as melted sulfur, cement and the like. By seating the tapered ends of the abrading blocks in corresponding apertures however, the assembling and dismantling of the abrading members is greatly facilitated.
- 10 While the abrading members are assembled in Figs. 7 and 8 it will be noticed that the same may be constructed in other forms within the meaning and scope of the following claims.
- 15 In the use of the invention the rotation of the grinding head causes a creeping of the machine along the floor or other surface being polished so that the same may be easily directed by the operator through the steering handle. In order to prevent the grinding head from coming into contact with the walls, posts or other obstructions and to avoid damaging the same a guard ring is preferably placed about the grinding head.
- 20 As illustrated herein this guard device comprises a metallic ring 75 which preferably extends entirely around the guiding head and is supported by three brackets 76, 77, 78 connected to said ring and to the sides and front of the extension 2 of the platform.
- 25 It will be further understood that the particular mechanisms disclosed herein are illustrative in character and are not restrictive and that various modifications in form, dimensions, arrangements, etc., may be made within the spirit of the following claims hereto annexed.
- 30 Having thus described my invention what I claim as new and desire to secure by Letters Patent is:
1. In a machine of the class described comprising a driving head and means for actuating the same; a plurality of non-revolvable polishing tools, each connected to said head by universal couplings to permit the independent tilting of each tool, each tool comprising a plurality of abrasive members rigidly secured thereto and so arranged as to be maintained at all times in contact with the surface being treated.
- 45 2. In a machine of the class described comprising a driving head and means for actuating the same; a plurality of polishing tools each connected to said head by universal couplings to permit the independent tilting of each tool, each tool comprising abrasive members rigidly secured thereto and arranged in triangular relation whereby said members will be maintained at all times in contact with the surface being treated and means for preventing rotation of said tools relatively to said head.
- 55 3. In a machine of the class described comprising a driving head and means for actuating the same; a plurality of polishing tools

each connected to said head by universal couplings to permit the independent tilting of each tool, each tool comprising a plate having apertures with upwardly converging walls, and abrasive members having tapering ends seated in said apertures, whereby the abrasive members may be readily removed and replaced.

4. In a machine of the class described comprising a rotary driving head and means for actuating the same; a series of three non-revolvable polishing tools connected to said head by universal couplings, to permit the independent tilting of each tool in any direction, each tool comprising a plurality of abrasive members disposed at different distances from the axis of rotation of said driving member adapted to be maintained at all times in contact with the surface being treated.

5. In a machine of the class described comprising a rotary driving head and means for actuating the same, a series of three non-revolvable polishing tools connected to said head by universal couplings, to permit independent tilting of each tool in any direction, each tool comprising abrasive members arranged in triangular relation and at different distances from the axis of rotation of said driving head whereby said abrasive members will be maintained at all times in contact with the surface being treated and paths provided for free circulation of water throughout the area engaged by said abrasive members.

6. In a machine of the class described comprising a rotary driving head and means for actuating the same; a series of polishing tools, each comprising three abrasive members, connected to said head by universal couplings to permit independent tilting of each tool in any direction, means to prevent rotation of said tools relatively to said head without interfering with the freedom of tilting of said tools, and means for limiting the amount of said tilting of said tools.

7. In a machine of the class described comprising a rotary driving head and means for actuating the same; a series of polishing tools connected to said head by universal couplings, lugs depending from said head loosely engaging adjacent ends of said polishing tools adapted to prevent relative rotation between said tools and said head but to allow independent tilting of said tools.

8. In a machine of the class described comprising a driving head and means for actuating the same; a series of polishing tools each having abrasive members arranged in triangular relation, a ball and socket connection between the driving head and each tool located within the area of the triangle formed by lines connecting said abrasive members and means for detachably

connecting the members of said ball and socket connection whereby the polishing tools may be readily removed.

9. In a machine of the class described comprising a driving head and means for actuating the same; a series of polishing tools each having abrasive members arranged in triangular relation, studs having substantially spherical ends removably secured in said rotary head engaging sockets in said polishing tools within the area of the triangle formed by lines connecting said abrasive members, apertured lugs upon said tool projecting upwardly and disposed upon opposite sides of said sockets, keeper plates engaging the spherical heads of said studs and said lugs and cotter pins removably secured in said lugs adapted detachably to retain said keeper plates.

10. In a machine of the class described comprising a driving head and means for actuating the same, a polishing tool comprising a plate having apertures with upwardly converging conoidal walls and cylindrical members having conoidal ends tapered to fit said apertures. 20

11. In a machine of the class described comprising a driving head and means for actuating the same, a polishing tool comprising a plate having apertures with upwardly converging conoidal walls extending through said head and cylindrical members having conoidal ends tapered to fit said apertures. 30

In testimony whereof, I have signed my name to this specification. 35

ERCOLE CAVICCHI.
